(57) **CLAIM**

I claim the ornamental design for a mirror with lamp, as shown and described.

DESCRIPTION

FIG. 1 is a perspective view of the mirror with lamp thereof. FIG. 2 is a front view of the mirror with lamp thereof. FIG. 3 is a rear view of the mirror with lamp thereof. FIG. 4 is a left side view of the mirror with lamp thereof. FIG. 5 is a right side view of the mirror with lamp thereof. FIG. 6 is a top view of the mirror with lamp thereof. FIG. 7 is a bottom view of the mirror with lamp thereof; and, FIG. 8 is a right side elevational view with the support leg in extended condition.

The broken lines are for environmental purposes only and form no part of the claimed design.
